UNITED STATES PATENT OFFICE.

ALBERT E. POWERS, OF LANSINGBURG, NEW YORK.

DESIGN FOR FLOOR OIL-CLOTH.

Specification forming part of Design No. 2,193, dated October 10, 1865.

To all whom it may concern:

Be it known that I, ALBERT E. POWERS, of the town of Lansingburg, in the county of Rennselear and State of New York, have invented or produced a new and original Design for Floor Oil-Cloths or other Fabrics; and I do hereby declare that the following is a full and exact description of the same, reference being had to the accompanying drawings which are hereby declared to be a part of this specification.

The pattern is in what is known as "Persian" style, having a ground striped in various colors, with appropriate ornaments upon the several stripes. Upon this ground at regular

intervals are placed figures of white ground in shape of an eight-pointed star, with various ornamental figures in colors upon them, the whole forming a pattern as shown upon the drawing.

What I claim as my invention, and desire to secure by Letters Patent, is—

The design for floor oil-cloths or other fabrics, as shown upon the accompanying drawings, and described in this specification.

ALBERT E. POWERS.

In presence of—

RICHARD GREEN,
CHAS. J. LANSING.
